6 Claims. (Cl. 118—49)

This invention relates to the continuous coating of a metallic or nonmetallic substrate in a vacuum. Before continuous coating could become an economically feasible process, it was necessary to develop efficient vacuum seals which would make possible the continuous introduction and removal of a substrate from high vacuum. The simplest and most straightforward method of accomplishing this end appeared to be the introduction and removal of the substrate through a series of chambers connected by low throughput apertures in the form of narrow slots. The leak thus introduced could be adequately controlled and a steep pressure gradient maintained by positioning vacuum pumps so as to reduce the pressure further in each successive chamber. However, all prior systems developed along these lines have involved objectionable features which rendered the processes economically unfeasible. The weightiest objection to these systems was the difficulty encountered in coping with the excessive leak caused by the throughput apertures mentioned above. These apertures were either so large as to cause pumping requirements to become excessive or so small as to materially interfere with the passage of the substrate. In the instant invention, due to the development of a novel type of vacuum seal and a completely novel arrangement of the seals, this problem has been successfully brought to a solution.

Accordingly, it is the primary object of this invention to provide a commercially satisfactory method of vacuum coating a continuously moving substrate, suitable substrates being sheet steel or iron, organic substrates such as the polyethylene terephthalate sold under the name of "Mylar" and the like.

Another object of the invention is to provide seals for a vacuum chamber in which a substrate is to be coated efficient enough to effectively reduce the leakage of air into the chamber to a relatively low figure.

Another object of the invention is to provide a throughput aperture into a vacuum chamber small enough to keep the pumping requirements at a reduced figure yet large enough to allow passage of a moving substrate without materially affecting the substrate.

Still another object of the invention is to provide a throughput aperture small enough to keep pumping requirements at an acceptable level yet large enough so as not to materially affect a weld of the type utilized to join two sheets of steel, iron or the like.

Other objects of the invention will in part be obvious and will in part appear hereinafter.

The invention accordingly comprises the process involving the several steps and the relation and the order of one or more of such steps with respect to each of the others and the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following

ing detailed description taken in connection with the accompanying drawings wherein:

Fig. 1 is a diagrammatic, schematic view of one preferred embodiment of the invention;

Fig. 2 is a diagrammatic, schematic view of the vacuum seal;

Fig. 3 is a diagrammatic, schematic cutaway view of Fig. 2 taken along the lines 3—3; and

Fig. 4 is a graph showing the pumping requirement per stage for a four-stage seal plotted against W/L (width/length) for various values of clearance (h).

In the instant invention, the vacuum seals are comprised of convex surfaces with close-fitting concave housings. A substrate is passed through the slots or openings between the convex surfaces and the housings. This substrate is kept taut and in contact with the convex surface, damage to the substrate due to abrasive rubbing against the sides of the slots thus being avoided. In the continuous coating of sheet steel or iron, this is particularly important as it is necessary to lap weld the ends of the individual sheets of metal together so that they can be fed to the coater. This lap weld is essentially incapable of withstanding a sharp blow and, therefore, all unnecessary contact between the moving welded sheets, especially that area of the sheets containing the welded joint, and objects capable of producing sharp blows or large amounts of abrasive rubbing must be avoided. The seal in the instant invention has been so designed as to allow welded sheets of iron or steel to be introduced and removed from a coating chamber without coming in contact with anything except the convex surface, which convex surface is, in a preferred embodiment, a roller. The substrate is held taut against the roller and away from the housing, thereby insuring complete lack of contact with anything but the roller.

However, the great advantage of the instant vacuum seal over seals of the prior art is due to the far more efficient reduction of the rate of leak in the present invention than was heretofore possible. The rate of leak through a narrow slot can be calculated from the following equation which results from a modified derivation of the Poiselle law equation:

$$m = \frac{Wh^3 M}{24LR\eta} (P_2^2 - P_1^2)$$

where

m is throughout in grams/sec.

h is clearance of slot in cm. (short dimension)

W is width of slot in cm.

L is length of slot in cm.

P_2 and P_1 are pressures in dynes/cm.²

R is gas constant in ergs/mole K.°

T is temperature in K.°

η is viscosity in poises

M is molecular weight in grams

Converting from throughput in grams/sec. to throughput in liter-microbars/sec.:

$$Q_{1b} = \frac{m}{M} RT = PV = \frac{10^{-3} Wh^3}{24L\eta} (P_2^2 - P_1^2)$$

Finally converting K_{1b} to Q_0 and solving for P_2 :

$$P_2 = \sqrt{P_1 \frac{Q_0}{W_h^3} + P_1}$$

where Q_0 equals the leak in c.f.m. at pressure P_1 .

It should be mentioned that, for short slots in which the velocity of gas is high, a certain reduction in throughput is observed due to turbulence at the ends of the slot. Several sample calculations of this type were made, and

it was found that, for values of W/L equal to less than 10, the end corrections are not significant.

Using the equation derived above, the pressure gradient along a multistage seal can now be determined, as has been done in Fig. 4 for several sets of values. The only restrictions on Fig. 4 are that (1) an equal volume of gas be pumped from each chamber and (2) the slots between chambers all have the same dimensions.

Referring now to Fig. 4, where pumping requirements per stage for a four-stage seal are plotted against W/L for various values of h , it becomes readily apparent that the length of the slot (L) is of great importance. Using, by way of example, a slot with a clearance (h) of 0.025 cm. (or 0.010 inch), we observe that, if the W/L ratio is 10, that is, if the slot is 10 times as wide as it is long, the pumping requirement per stage is about 75 c.f.m. If, on the other hand, the W/L ratio is equal to 1, the pumping requirement per stage is about 7.5 c.f.m. The seal of the present invention makes maximum use of this relationship.

Referring now to Figs. 1, 2, 3 and 4, wherein like numbers refer to like parts, there is indicated schematically one embodiment of the invention wherein a substrate such as sheet iron or steel can be vacuum coated. This preferred embodiment of the invention consists of four chambers 1, 2, 3 and 4 and a coating chamber 15, all of which are connected by means of vacuum seals 8 set into the walls 14 of the vacuum chambers. These four chambers can be maintained at a steep pressure gradient, the pressure decreasing from atmospheric pressure outside chamber 1 to well below a millimeter of pressure inside the coating chamber. A substrate 11 is guided by means of a series of vacuum seals through the four vacuum chambers 1, 2, 3 and 4 into the high vacuum chamber 15, over a source of coating vapors 16, and then is guided by means of another series of vacuum seals out of the system.

Each seal is comprised of a narrow slot 9 between a rotatable, cylindrical roller 12 and a stationary housing 10. In a preferred embodiment of the invention, this slot is a groove in the periphery of the roller on the side of the roller facing the housing. The clearance of the slot should not be more than 0.050 inch and the W/L ratio should be less than 10 if the pumping requirements are to be within the limits of what is commercially practicable. Suitable brushes 13 of bronze, graphite or the like are utilized to prevent excessive leakage of air through the groove 9 in the roller 12 along that part of the housing 6 opposite which the roller 12 does not come in contact with the substrate 11.

In the preferred embodiment of the invention shown in the drawings, the seal 8 is so designed as to cause the substrate to follow an arcuate path of at least 120°. A rotary seal is preferred to a linear seal because of the above mentioned difficulties that would otherwise result due to the lap weld and because, if the air leaking from one chamber to another is made to follow an arcuate path, the amount of air reaching the succeeding chamber is still further reduced.

The optimum size of the slot varies in accordance with the particular substrate being utilized. For sheet steel that is 30 inches wide and 0.010 inch thick, the clearance slot should be about 0.030 inch in order to allow for the passing of a weld. If the sheet is kept very close to one wall of the slot (in the instant case, it is held taut against the groove in the roller surface), the actual leak is determined by the clearance between the sheet and the opposite wall. In this particular case, since the slot has a clearance of 0.030 inch and the sheet is 0.010 inch thick, the net clearance would be 0.020 inch (or 0.050 cm.). If the length of the slot (L), which length is the linear length of the arc which the sheet describes while within the housing, is 30 inches, then W/L equals 1 and, therefore, the pumping requirement per chamber is 60 c.f.m., as indicated by Fig. 4.

Using a sheet of the same specifications as the sheet in the example above and assuming the length of the slot to be 3 inches instead of 30 inches, the value obtained from the graph for the pumping requirement per stage is about 600 c.f.m. Therein lies the great advantage of the instant system over all prior systems. The 60 c.f.m. is an entirely acceptable figure, whereas the 600 c.f.m. pumping requirement per stage is almost impossible to meet and certainly is entirely impractical from the commercial point of view.

It should be pointed out that the same restrictions mentioned above as regards Fig. 4 apply to these calculations also. Actually, it is not necessary that the restriction regarding an equal volume of gas to be pumped from each chamber be absolute. There is some evidence tending to indicate that pumps arranged in decreasing capacities, the largest pump in the chamber closest to the atmosphere, would actually result in a greater pumping efficiency than is realized in the above arrangement. However, for the sake of simplicity, the assumption that equal volumes of gas were being pumped from each chamber was adhered to.

Referring now to the above calculated example for the purposes of illustration, it has been experimentally shown that it is extremely difficult to draw sheet steel in a straight line under high tension through a slot of this length without causing damage to the sheet, the slot and especially the lap weld. But, in the instant application, due to the use of curved rotary seals, the aforesaid difficulty is avoided.

In still another preferred embodiment, the entrance end of the seal in vacuum chamber 1 is connected directly to an atmosphere furnace used for drying and outgassing the substrate after cleaning. This embodiment of the invention comprises precleaning a sheet of metal such as steel and then, without allowing the sheet to come in contact with the atmosphere, passing it through an oxygen-free barometric leg, subsequently flash-drying it, and finally passing it into the above described vacuum system so that it can be coated. In a slight modification of the above procedure, the sheet, after precleaning and while under a nonoxidizing atmosphere, is passed through a nonoxidizing bath, subsequently flash-dried under a nonoxidizing atmosphere, and then fed into a vacuum-coating system of the type described above without any exposure to an oxidizing atmosphere prior to coating. This procedure has, in many cases, been found to remarkably improve the adherence of the coating to the metal substrate. The nonoxidizing atmosphere mentioned above is comprised of either a reduced pressure or an inert or reducing atmosphere.

In still another embodiment of the invention, an aspirator is used to preclean a sheet of steel and to reduce the pressure so that the sheet can be easily dried. Subsequently, of course, the sheet is passed into a vacuum system of the type claimed in order to be coated.

Since certain changes may be effected in the above process without departing from the scope of the invention herein involved, it is intended that all matter contained in the above description, or shown in the accompanying drawings, shall be interpreted as illustrative and not in a limiting sense.

What is claimed is:

1. In apparatus for vacuum coating a continuously traveling material, said apparatus consisting of a plurality of vacuum chambers, separate means to reduce the pressure in said chambers, means to provide coating vapors within one of said chambers, and means for guiding said substrate over said coating vapors, the improvement which comprises means for providing vacuum seals in the walls of one of said vacuum chambers to allow passage of said substrate into and out of said vacuum chamber, said vacuum seals comprising a roller and a close-fitting housing for said roller, the opening between said roller and housing being not wider than 0.050 inch,

said substrate following an arcuate path around said roller, said path describing an arc of between 120 and 180 degrees, and means for holding the substrate taut against said roller in order that contact between the substrate and the housing be prevented.

2. In apparatus for vacuum coating a continuously moving substrate, said apparatus consisting of a plurality of vacuum chambers, separate means to reduce the pressure in said vacuum chambers, means to provide coating vapors within one of said chambers, and means for guiding said substrate over said coating vapors, the improvement which comprises means for providing at least two vacuum seals in the walls of one of said chambers to guide said substrate into and out of said vacuum chamber, each said vacuum seal comprising a roller, a close-fitting housing for said roller, said substrate following an arcuate path around said roller, the ratio of the width to the linear length of said path being less than 10, said path describing an arc of at least 120 degrees, said roller having a groove extending circumferentially about its periphery, means for holding the substrate taut against said groove in said roller in order that contact between the substrate and the housing be prevented, said housing containing brushes along that part of its circumference opposite which the roller does not come in contact with

15

20
25

the substrate in order that leakage of air into the succeeding vacuum chamber be further reduced.

3. The apparatus of claim 2 wherein the groove in said roller is less than 0.050 inch in depth.

4. The apparatus of claim 2 wherein a groove of less than 0.050 inch is placed in the housing instead of the roller.

5. The apparatus of claim 2 wherein said vacuum chamber is a plurality of vacuum chambers interconnected by means of vacuum seals of the type claimed.

10 6. The apparatus of claim 2 wherein there are four vacuum chambers and a coating chamber all interconnected by means of vacuum seals of the type claimed.
